CHAIR

Morris F. Fisher, 9820 Deerfield Circle,
Carmel, Ind. 46032

Filed Apr. 27, 1971, Ser. No. 138,019

Term of patent 14 years

Int. Cl. D6—02

U.S. Cl. D6—69

The figure is a perspective view of a chair illustrating my new design.

The back of the chair is conventionally plain while the side not shown is substantially identical to the side shown.

I claim:

The ornamental design for a chair, as shown and described.
